DESIGN FOR A DOG BED

Robert L. Richardson, Eden, N. Y.

Application November 5, 1941, Serial No. 104,028

Term of patent 7 years

To all whom it may concern:

Be it known that I, Robert L. Richardson, a citizen of the United States, residing at Eden, in the county of Erie and State of New York, have invented a new, original, and ornamental Design for a Dog Bed, of which the following is a specification, reference being had to the accompanying drawing forming part thereof.

In this drawing:

Fig. 1 is a perspective view of a dog bed embodying my new design.

Fig. 2 is a front elevational view thereof.

Fig. 3 is a top plan view thereof.

Fig. 4 is a vertical cross sectional view of the same taken on line 4—4, Fig. 3.

Fig. 5 is an enlarged, fragmentary, horizontal sectional view taken on line 5—5, Fig. 2.

I claim:

The ornamental design for a dog bed, as shown.

ROBERT L. RICHARDSON.
